UNITED STATES PATENT OFFICE.

JOHN SCHUSTER, OF CLAY BANKS, WISCONSIN.

CONVERTIBLE HAY AND STOCK RACK.

No. 800,175.

Specification of Letters Patent.

Patented Sept. 26, 1905.

Application filed May 5, 1905. Serial No. 269,074.

To all whom it may concern:

Be it known that I, JOHN SCHUSTER, a citizen of the United States, residing at Clay Banks, in the county of Door and State of Wisconsin, have invented a new and useful 5 Convertible Hay and Stock Rack, of which the following is a specification.

This invention relates to convertible hay or stock racks, and has for its object to provide 10 a device of this class formed of separable parts which may be readily united to form a hay-rack, stock-rack, wood or lumber rack, or similar structure and disposed upon the running-gear of a vehicle and as easily separable for removal from the running-gear when required. 15

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred 25 form of embodiment of the invention capable of carrying the same into practical operation, it being understood that the invention is not necessarily limited thereto, as various changes in the shape, proportions, and general assembly 30 of the parts may be resorted to without departing from the principle of the invention or sacrificing any of its advantages.

In the drawings thus employed, Figure 1 is a plan view of the device arranged as a hay-rack. Fig. 2 is a transverse section on the line 2 2 of Fig. 1. Fig. 3 is a transverse section on the line 3 3 of Fig. 1. Fig. 4 is a sectional detail illustrating the construction of the end members of the body portion. Fig. 5 is a perspective view of a portion of one of the side members of the body portion. Fig. 6 is a perspective view of a portion of one of the end clamp-bars. Fig. 7 is a perspective view of the intermediate portion of one of the side members of the body portion. Fig. 8 is a perspective view of the lower end of one of the side members of the "ladder." Fig. 9 is a perspective view, enlarged, of one of the clips used on the intermediate clamp-bars. Fig. 10 is a 45 transverse section of the device arranged as a stock-rack. Fig. 11 is a perspective view of a portion of one of the vertical members of the end portion employed when the device is arranged as a stock-rack. Fig. 12 is a perspective view of the upper end of one of the 50

end members employed when the apparatus is employed as a stock-rack.

The improved device comprises two spaced side members 10 11, having centrally-disposed sockets 12 13 attached, respectively, to their inner faces for supporting a transverse tie member 14, the sockets having depending ears 15 16 to receive the bent ends of a tie-rod 17. Thus the tie-rod prevents the side members from separating laterally, and the tie member 14 prevents the side members moving toward each other. Extending transversely beneath the forward ends of the side members 10 11 is a stay-bar 18, and extending in the same manner over the top of the side 70 members is a stay-bar 19, the two bars connected by spaced tie-bolts 20 21. Attached to the outer ends of the bar 18 are L-shaped clips 22 for bearing beneath the side members 10 11 and extending for a distance up 75 the outsides of the same, and similar clips 23 are connected to the bar 19 for bearing over the upper portions of the side members. At the rear ends the side members 10 11 are provided with bars 24 25 and clips 26 27, similar 80 to the forward ends, and with tie-rods 28 29, similar to the tie-rods 20 21, the whole forming a very rigid and strong box or body which will firmly support the superstructure. 85

One of the end bar-clips, as 23, is illustrated in Fig. 9, and as all the clips of the end bars are precisely alike the one illustration will answer for all. Each of the clips for the end bars is provided with an internal wing 49 for passing through the end of the bar 90 members and extending beyond the same for entering cavities in the side members 10 11, and thus serve effectually to prevent lateral movement between the bars and side members. 95

The bottom boards 56 rest upon the end bars 18 and 24 and also upon the bar 14, as indicated.

The side members 10 11 are provided, respectively, with spaced transverse apertures 100 30 31 to receive the lower ends of cross-bars 32 33, the reduced ends of the bars 32 being inserted in the apertures 31 and extending in an upwardly-inclined direction over the side member 10 and bearing upon the same, and 105 the cross-bars 33, similarly arranged relative to the apertures 30 in the side member 10 and the upper edge of the side member 11. The cross-bars thus pass each other centrally 110 of the body formed by the members 10 11, as

shown, and are arranged at suitable intervals and any required number may be employed, but generally four pairs will be employed, as shown in Fig. 1.

5 Disposed upon the inner faces of the side members 10 11 near the forward ends are brackets 34 35, upon which other brackets 36 37 upon the foot ends of the ladder member 38 bear and secured thereto, as by clamp-bolts 39 40, the ladder being further supported by brace-hooks 41 42 from the side members 10 11. The converging upper ends of the side members of the ladder 38 are coupled by a bracket 43, having apertures 44 15 to receive the butt or forward end of the binding member, the bracket being extended into a rein-guiding fork 45.

The binding-poles commonly employed upon hay-racks will be used in connection 20 with the device; but as these devices are so well known it is not deemed necessary to illustrate the same. Hooks 69 70 are attached to the rear ends of the side members 10 11 to receive the draw-cable by which the rear end 25 of the binder-pole is secured.

The forward pair of the cross-bars 32 33 bear against the inner sides of the ladder member 38, and the latter bears against the adjacent side of the tie-bar 19, while the rearmost 30 pair of the cross-bars bear against the inner face of the tie-bar 25.

Disposed between the intermediate pairs of the cross-bars 32 33 are tie-bars 46, having L-shaped clips 47 48 at the ends for bearing 35 over the upper edges of the members 10 11, the clips having spaced ribs for entering small recesses in the upper edge of the side members. The clips attached to the tie-bars 46 are all alike, and one of them is shown in perspective and inverted in Fig. 9 to illustrate 40 the interior construction of the ribs, (represented at 60,) and in the upper edges of the members 10 11 recesses are formed to receive these ribs, one of the recesses being shown 45 at 50 in Fig. 7, which represents a portion of one of the side members in perspective at the point where one of the recesses is disposed. It will be understood that one of the recesses 50 will be formed in the upper edges of the 50 members 10 11 wherever the clips 47 48 are disposed. The ribs 60 serve to prevent lateral movement to the binder members 46, and thus add materially to the stability of the structure without materially increasing the 55 weight or expense of manufacture.

Disposed transversely of the extended portions of the cross-bars 32 33 are spaced rack boards or slats 51, each slat having spaced longitudinal slots 52, through which bolts 53 60 pass, one end of the bolts having transverse heads 54 for extending transversely of the slats and the threaded ends of the bolts for passing through the members 32 33 and provided with nuts 55, bearing beneath the same. 65 The terminals of the heads 54 have depend-

ing lips for bearing over the edges of the slats 51, as shown in Fig. 2, and when the nuts 55 are set up it will be obvious that the slats will be firmly clamped to the cross-bars. The slots 52 will permit the slats 51 to be detached when the nuts 55 are loosened and the heads turned to register with the slots, the bolts thus remaining in the cross-bars. 70

By this means a complete hay-rack structure is provided which is strong and durable 75 and may be employed for all the purposes for which hay-racks and similar structures are usually employed.

All the parts being easily separable, the device may be taken apart in a short space of 80 time and stored for future use and as readily reassembled when required.

Each separate part being comparatively 85 small can be easily handled by one person and will not require the employment of hoisting means or power of any kind to remove or attach the rack.

End members 80 are inserted, respectively, 90 between the end bars 18 19 and the end bars 24 25, with transverse cleats 58 59, the ends 95 of the cleats extended for entering recesses in the end bars, as shown in Fig. 4, which represents a transverse section of one of the end members and the adjacent end bars.

By detaching the ladder member 38 tie-bars 95 46 and cross-bars 32 33, together with the spaced slats 51, connected thereto, the body portion of the device is left free of any superstructure whatever and is then in the form of an ordinary wagon-box and can be employed 100 as such.

The stock-rack portion of the device comprises a plurality of vertical standards 71, each having a clip 72 attached at one end and terminating in longitudinally-extended hooks 105 for insertion from the outside through the apertures 30 31 in the side members 10 11, as shown in Fig. 10, the standards each having a catch-rod 74 therethrough and each formed with a terminal hook 75 for bearing over the upper edges of the side members 10 11 and entering cavities 61 therein, one of the cavities being shown in Fig. 7. The standards are provided with hook-bolts 78 to support side slats 62 at spaced intervals and in horizontal position. The standards that come at the ends of the side members have open slots in their upper ends to receive tie-rods, one of which is shown at 63 and provided with wing-nuts 64 65, bearing against the outer faces of the standards, and thus prevents the spreading 110 of the standards under the strains to which they are liable to be subjected. 115

End closures are provided to be disposed 120 between the side rack formed by the standards 71 and spaced slats 62, one of which is shown in Fig. 10, and consists of standards 66 67, connected at the upper converging ends by a metal strap 68, the ends of the strap projecting laterally and slotted, as at 81, to bear 125 130

over the tie-rod 63, while the lower ends of the standards 66 67 are provided with clips 76 77, bolted to the end bars 19 and 25. Spaced slats 69 are bolted to the standards 66 67 and 5 extend to the side slats 62. The end closures are precisely alike and connected in the same manner, and the illustration and description of one only are deemed sufficient.

The stock-rack members are readily detachable and can be easily handled by one person, as will be obvious.

The whole device is simple in construction, can be inexpensively manufactured, and is strong and durable when assembled, while at 15 the same time readily separable when required.

By omitting the side slats 62 from the standards 71 and removing the end closures of the stock-rack portion the device may be employed as a wood-rack or for like purposes.

The side members of the ladder 38 are provided with spaced apertures 82 to provide means for attaching the end slats 69 thereto instead of employing the members 67, if required.

Having thus described the invention, what is claimed is—

1. In a device of the class described, a body having spaced side walls provided with trans- 30 verse recesses in the upper side and trans- 30 verse apertures near the lower sides, cross- 30 bars reversely inclined and respectively en- 30 gaging said apertures and extending in oppo- 35 site directions over said side walls, tie mem- 35 bers disposed between each pair of said cross- 35 bars, and clips connected to said tie members 40 and bearing over said side walls and provided 40 with lateral ribs for engaging the recesses in 45 the same.

2. In a device of the class described, a body having spaced side walls provided with trans- 45 verse apertures, cross-bars arranged in pairs 45 and reversely inclined and respectively en- 50 gaging said apertures and extending in oppo- 50 site directions over said side walls, spaced 50 slats extending transversely of said cross- 50 bars, means for detachably coupling said slats 55 to said cross-bars, tie members disposed be- 55 tween each pair of said cross-bars, and clips 60 connected to said tie members and bearing 60 over said side walls.

3. In a device of the class described, a body having spaced side walls provided with trans- 55 verse apertures, cross-bars arranged in pairs 55 and reversely inclined and respectively en- 60 gaging said apertures and extending in oppo- 60 site directions over said side walls, spaced 60 slats extending transversely of said cross-bars 65 and provided with spaced longitudinal slots, 65 clamp-bolts operating through said cross-bars and having laterally-extending heads for passing through said slots and extending trans- 70 versely of the slats, tie members disposed be- 70 tween each pair of said cross-bars, and coup-

ling means between said tie members and side 65 walls.

4. In a device of the class described, a body having spaced side walls and provided with transverse apertures and with inwardly-extending brackets at the forward end, cross-bars 70 reversely inclined and respectively engaging said apertures and extending in opposite directions over said side walls, tie members disposed between each pair of said cross-bars, coupling means between said tie members and side walls, a ladder member bearing upon said brackets and having clips engaging the same and bolted thereto, and brace-rods between said ladder member and side walls.

5. In a device of the class described, a body 80 having spaced side walls provided with trans- 80 verse apertures, cross-bars reversely inclined 80 and respectively engaging said apertures and 85 extending in opposite directions over said side 85 walls, tie members disposed between each pair 90 of said cross-bars, coupling means between 90 said tie member and side walls, a ladder mem- 90 ber formed with upwardly-converging sides 95 connected at the upper end by a frame pro- 95 vided with transverse apertures, and means 100 for detachably supporting said ladder from 100 said body.

6. In a device of the class described, a body having spaced side members, transverse tie- 95 bars bearing upon the opposite edges of said 95 side members at the ends, tie-bolts connect- 100 ing each opposite pair of said tie-bars, and 100 clips attached to said tie-bars and bearing over 105 the adjacent portions of the said side mem- 105 bers.

7. In a device of the class described, a body having spaced side members, sockets connect- 105 ed to said side members and provided with 110 depending perforated ears, a tie-rod connect- 110 ing said ears, a tie-bar bearing within said 110 sockets, transverse tie-bars bearing upon the 115 opposite edges of said side members at the 115 ends, tie-bolts connecting each opposite pair 120 of said tie-bars, and clips attached to said tie- 120 bars and bearing over the adjacent portions 125 of the said side members.

8. In a device of the class described, a body having spaced side members, transverse tie- 125 bars bearing upon the opposite edges of said 125 side members at the ends, tie-bolts connect- 130 ing each opposite pair of said tie-bars, clips 130 attached to said tie-bars and bearing over the 135 adjacent portions of said side members, and 135 end members disposed between said spaced 140 sides at the ends and provided with transverse 140 cleats having the ends projecting for engag- 145 ing recesses in said tie members.

9. In a device of the class described, a body having spaced side members provided with spaced transverse apertures, transverse tie- 145 bars bearing upon the opposite edges of said 145 side members at the ends, tie-bolts connect- 150 ing each opposite pair of said tie-bars, clips 150

attached to said tie-bars and bearing over said side members, cross-bars reversely inclined and respectively engaging said apertures and extending in opposite directions over said side members, tie members disposed between each pair of said cross-bars, and coupling means between said tie members and said side members.

In testimony that I claim the foregoing as my own I have hereto affixed my signature in the presence of two witnesses.

JOHN SCHUSTER.
